UNITED STATES PATENT OFFICE.

ALBERT C. LUYCKX, OF DETROIT, MICHIGAN.

BARREL-MACHINE.

SPECIFICATION forming part of Letters Patent No. 694,167, dated February 25, 1902.

* Application filed June 8, 1901. Serial No. 63,698. (No model.)

To all whom it may concern:

Be it known that I, ALBERT C. LUYCKX, a citizen of the United States of America, residing at Detroit, in the county of Wayne and 5 State of Michigan, have invented certain new and useful Improvements in Barrel-Machines, of which the following is a specification, reference being had therein to the accompanying drawings.

This invention relates to that class of barrel-machine designed for forming barrel-bodies from wood veneer; and my invention consists in the improved construction, arrangement, and operation of an expansible forming-cylinder and in the means for compressing the veneer in the act of forming the barrel-body, all as more fully hereinafter described, and shown in the accompanying drawings, in which—

Figure 1 is a vertical central longitudinal section through the machine. Figs. 2 and 3 are the two end elevations thereof, respectively. Fig. 4 is a side elevation thereof. Fig. 5 is a cross-section on line 5—5, Fig. 1. Fig. 6 is a detail perspective view of the sliding connection between the segments and the supporting-arms thereof, and Fig. 7 is a perspective view of the clamping-strip.

A is the shaft upon which the expansible forming-cylinder is mounted.

B is the supporting-frame, with vertical standards C C', provided with bearings D D' for the shaft.

The standard C is formed with a hinge-joint at E and terminates at its upper end in a half-bearing D, adapted to support the trunnion a, formed at the end of the shaft, all so arranged that the upper section of the standard C can be moved out of the way to permit the removal of the barrel from the cylinder after it is formed.

The forming-cylinder is composed of segments F, the drawings showing four such segments, which collectively form a metal cylinder, with peripheral grooves b b near the ends, 45 made of a size to receive the inner hoops for the barrel-body, the depth of the grooves being the thickness of the hoops. This forming-cylinder is made expansible in the following manner: Each segment is formed with a 50 pair of radial arms c, terminating at their inner ends in bearings c', having inclined undercut mortises which slidingly engage with cor-

respondingly-inclined tenons d. The tenons at each end of the cylinder are carried by spider-cones G G, which are sleeved upon the 55 shaft and connected together by the tube H, whereby both move together.

The shaft A has at one end a screw-threaded portion e, which carries a nut f, provided with a hand-wheel I for turning it. This nut at its 60 inner end abuts against the hub of the adjacent spider-cone and has an annular flange h, by means of which the nut is held in contact with the spider-cone through the coupling-sleeve j, screwed upon the hub of the spider-cone, all so arranged that the nut is free to turn independently of the spider-cone, but carrying the cone with it. As both cones must move together, it will be seen by turning the hand-wheel the cones can be moved along the 65 shaft in either direction, and as these cones carry the inclined tenons the latter will impart to the segments a radial expanding or contracting movement. The segments are held against lateral displacement and radially 70 guided in their movement by a spider J, secured upon the shaft A and having bifurcated arms, into which the radial guide-lugs i on the inner side of the segments engage and in which they are guided by pins k, engaging into radial slots l in the ends of the spider-arms.

The rear side of the frame has two upwardly-projecting supports K, in which is secured a transverse bar L, which forms the fulcrum for the power-lever M, which is 85 forked at its upper end and fulcrumed upon the bar L by means of bearings L' in the forked ends of the lever. The long arm of this lever projects vertically downwardly below the fulcrum and thence forwardly, terminating in a footpiece m in convenient position for the operator to place his foot upon for actuating the lever.

The short arm of the lever M extends upwardly above the fulcrum and terminates 90 above the center of the forming-cylinder, and to the bifurcated ends of this short arm is fixedly secured the compressor-bar N, all so arranged that the operator by stepping upon the footpiece m of the lever will press the 100 bar N against the face of the forming-cylinder. In this position the lever M may be locked by engaging it with one of the rack-teeth n, formed in a guide-loop O, through

which the lever M passes, a suitable spring n' being provided to normally hold the presser-bar out of contact with the drum. The long arm of the lever is formed rigid; but the ends 5 forming the short arm are made of spring metal, so as to be slightly yielding when the compressing-bar is forced down upon the forming-cylinder. The compressing-bar is made rounding upon its lower side, where it 10 presses upon the forming-cylinder.

For revolving the forming-cylinder a gear-wheel P is fastened upon the end of the shaft near the fixed bearing D', and intermeshing therewith is a pinion R, supported upon the 15 frame in handy proximity to the operator in front of the machine and adapted to be revolved by a crank-handle, all so arranged that one complete turn of the handle will revolve the forming-cylinder the exact distance 20 apart at which it is desired to nail the outer hoops to the barrel-body.

My machine is designed for making barrels from veneer and is operated in the following manner: To begin with, the forming-cylinder 25 is first contracted. Then two complete hoops are slipped upon the cylinder into the annular grooves b, after which the forming-cylinder is again expanded till the hoops are so tightly bound in the grooves that they are 30 compelled to revolve with the cylinder during the formation of the barrel. The barrel is formed by inserting the edge of a sheet of veneer of suitable width under the compression-bar, clamping the same down tight upon 35 the former, and revolving the barrel intermittently by turning the crank one turn at a time, while a second operator standing on the rear side keeps nailing on the veneer to the inner hoops. New sheets of veneer are added 40 as needed to complete the barrel, and the outer hoops are secured around in the same way, all in the well-known manner and forming no part of this invention.

As the forming-cylinder is of metal, it is 45 obvious that the nails will become clenched upon the inside, and after the barrel is thus formed the forming-cylinder is collapsed and the barrel removed.

The advantage of my construction is that 50 I can make perfect single or double ply veneer barrels from absolutely dry and seasoned veneer, as the compression-bar (which does not roll, as in the other machines) being at the end of a power-lever presses the veneer so 55 tightly that it is forcibly stretched and all wrinkles or inequalities are straightened out, while at the same time the forming-cylinder is uniformly and evenly expanded by the action of a screw to the limit of the hoops with- 60 out danger of bursting the same or allowing the forming-cylinder to contract during the operation, so that the hoops are firmly held in the grooves and cannot slip.

In Fig. 7 I have shown a clamping-strip P, 65 formed with a hook o at one end, an apertured ear o' at the other end adapted to fit over the drum and hold the end of the veneer

or hoops against the face of the drum in making a barrel, a suitable wedge o² being inserted in the apertured ear to hold the clamping-bar down, or I may, if desired, dispense with the clamping-bar entirely and use a series of cams or other convenient means to accomplish this purpose. The clamping-bar is preferably slightly inwardly curved, so as to have a uniform clamping effect across the 75 face of the drum.

What I claim as my invention is—

1. In an expansible forming-cylinder, composed of a plurality of segments, the combination of a shaft journaled in bearings free to revolve and provided at one end with a screw-thread, a nut upon said screw-threaded portion of the shaft, a pair of connected cones sleeved upon said shaft and adapted to be 80 actuated by said nut to slide longitudinally of the shaft, a pair of radial arms on each segment projecting with their inner ends toward the faces of the cones respectively, a sliding connection between the inner ends of 85 said arms and the faces of the cones adapted to expand and contract the segments by the 90 sliding movement of the cones and means for radially guiding the segments in relation to the shaft.

2. In an expansible forming-cylinder, composed of a plurality of segments, the combination of the shaft A journaled in bearings and provided at one end with the screw-threads e, the nut f upon said screw-threads 100 having the hand-wheel I, the cone-spiders G G sleeved upon the shaft and connected to move together, the coupling-sleeve j uniting the screw-nut with the hub of one of the cones, free to revolve the nut independently 105 of the cones, the tenons d formed on the cones, the radial arms c of the segments provided with bearings c' having undercut mortises engaging with the tenons on the cones, the spider J fixed upon the shaft and having bifurcated arms, and the radial arms i of the segments guided in said bifurcations.

3. In a barrel-machine, the combination with the frame and forming-cylinder supported in said frame free to revolve, the combination of the power-lever M fulcrumed in rear of the forming-cylinder and having a rigid long arm extending in rear and beneath the frame and forming a foot-lever, a guide-loop O through which said foot-lever passes 115 and having ratchet-teeth for engaging said lever, a flexible short arm bifurcated and extending upwardly over the rear of the forming-cylinder, and a compression-bar rigidly secured to the bifurcated ends of the short 120 arm and extending longitudinally over the top of the forming-cylinder.

In testimony whereof I affix my signature in presence of two witnesses.

ALBERT C. LUYCKX.
